UNITED STATES PATENT OFFICE.

JOHN W. MORGAN, OF SAN ANTONIO, TEXAS, ASSIGNOR, BY MESNE ASSIGNMENTS, TO THE TENNESSEE FELT MANUFACTURING COMPANY, OF WEST NASHVILLE, TENNESSEE.

MATTRESS-MACHINE.

SPECIFICATION forming part of Letters Patent No. 664,882, dated January 1, 1901.

Application filed September 12, 1898. Serial No. 690,776. (No model.)

To all whom it may concern:

Be it known that I, JOHN W. MORGAN, a citizen of the United States of America, and a resident of San Antonio, in the county of Bexar and State of Texas, have invented certain new and useful Improvements in Mattress-Machines, of which the following is a specification.

My invention is an improved machine for making mattresses from lint-cotton and the like materials, which is compressed into a bat, ejected from the press, and in the process of being so ejected inserted in the tick.

One object of my invention is to provide improved means whereby the press-box and follower may be varied in operative width to adapt the machine for making mattresses of various widths.

A further object of my invention is to provide an improved machine in which a pair of press-boxes revolvable on a common axis are employed and adapted to be alternately disposed under a follower and a distributing or feed box, so that the material may be compressed into a mattress in one press-box while the other is being filled with lint to make another mattress.

A further object of my invention is to provide improved means for stiffening the compressed mattress-bat while the same is being inserted into the tick to facilitate the insertion thereof into the tick.

My invention consists in the peculiar construction and combination of devices herein-after fully set forth, and pointed out in the claims.

In the accompanying drawings, Figure 1 is a side elevation, partly in section, of a mattress-making machine embodying my improvements. Fig. 2 is an end elevation of one of the press-boxes, showing the same in operative position under the follower or press-block. Fig. 3 is a horizontal longitudinal sectional view taken on the line $x-x$ of Fig. 1. Fig. 4 is a detail top plan view of the extensible section of the press-block or follower employed for increasing the width of the press-block or follower. Fig. 5 is a detail transverse sectional view of the same. Fig. 6 is an enlarged detail sectional view of the

same, showing the extension-piece secured to one side of the follower. Fig. 7 is a top plan view of the same. Fig. 8 is a vertical longitudinal sectional view of one of the press-boxes, showing a mattress in process of being compressed therein. Fig. 9 is a vertical transverse sectional view of the same. Fig. 10 is a view similar to Fig. 8, showing the manner of ejecting the mattress-bat from the press-box and of forcing the same from the press-box into the tick. Fig. 11 is a detail perspective view of one of the upper stiffening-slats adapted to be attached to the under side of the follower. Fig. 12 is a similar view of one of the lower stiffening-slats adapted to be attached to the bottom of the press-box.

The press-boxes A and A' are constructed, preferably of wood, in any suitable manner and are adapted to be supplied at their upper ends with the cotton or material for the mattresses from a distributing-box K. The said distributing-box is provided with revolvable beaters, (indicated at N,) which serve to distribute the lint-cotton evenly throughout the area of the distributing-box and cause the same to fall by gravity from the distributing-box into the press-box below the distributing-box. The cotton is fed to the distributing-box through a chute, (indicated at I,) and the beaters are rotated by any suitable means. Said beaters are disposed transversely in the distributing-box and comprise radial arms N', which project from their shafts near the sides of the distributing-box and carry transversely-disposed fans N², 85 which extend across the distributing-box. The press-boxes are connected together for simultaneous movement around a common vertical axis which is formed by a vertical shaft C, and the two press-boxes are arranged to work in connection with the distributor and feeder K and the vertically-movable follower or press-block L. The said follower is in the form of a block and is provided with side extensions, which may be attached thereto, so that the width thereof may be varied to suit the width of the press-boxes, which is also variable by the means, in the manner, and for the purpose presently described herein. In the operation of the machine the material 100

is fed into one press-box from the distributor K, after which the press-boxes are turned on the vertical shaft, so as to bring the filled box below the follower. At this stage in the operation of the machine the empty press-box is below the distributor K, while the filled or partly-filled press-box is below the follower L, which may now be lowered for the purpose of compressing the material in the said press-box to form a bat or felt thereof of the required thickness of a mattress and of suitable density, while the other press-box is being supplied with material from the distributor K.

15 The press-boxes A A' are of suitable dimensions, usually about six feet in length, five feet in width, and six feet in height, and said press-boxes are provided with movable side boards D D'. A pair of iron brackets B, having central openings through which the shaft C extends, serve to connect the proximate inner sides of the press-boxes together. The shaft C is secured at its upper and lower ends, as shown, or in any other suitable manner to 20 the floor and ceiling of a building in which the machine is located. The movable side boards D D' are each provided, respectively, with brackets E E', which project beyond the ends thereof and are provided with threaded 25 openings, forming traveling nuts which operate in horizontal slots 25 in the end boards 26 of the boxes. Adjusting-screws F F' engage the said brackets E E' and serve to adjust the side boards D D' laterally, as may be 30 required to narrow or widen the press-boxes. The said adjusting-screws F F' are supported against endwise movement in suitable bearings in the uprights of the framework of the end boards, as shown in Figs. 2 and 3. Collars G G', with which said set-screws are provided, serve to prevent the same from moving longitudinally, and said adjusting-screws are further provided with angular heads H H', adapted for the attachment of a wrench or 35 handle, whereby the said adjusting-screws may be turned. In practice the said side boards D D' may be adjusted so as to make the width of the press-boxes from two feet six inches to five feet, according to the size 40 of the mattresses to be made.

The end boards of the boxes are provided with openings M M' of suitable width and height, said openings being at the lower sides of the said end boards and at the lower sides 45 of the press-boxes, the bats or felts passing through said openings in the process of being ejected from the press-boxes and inserted in the ticks. Tick-holders W, comprising metallic plates, preferably iron or steel, secured 50 at the upper and lower sides of the said openings M M', form spouts or mouths through which the bats pass while being ejected from the press-boxes and further serve to hold the ends of the ticks open, the open end of the 55 tick being passed over said tick-holders before the cotton-bats are ejected from the press-boxes, so that as the same pass out through

the openings M M' they are inserted in the ticks.

It is of importance to stiffen the bats to facilitate the introduction thereof into the ticks, and to effect this I employ two series of stiffening-slats 21 23. The slats 21 are the upper slats, adapted to bear upon the upper side of the bat, and the slats 23 are the lower slats, 70 adapted to bear under the bottom of the bat. The follower is provided on its lower side with longitudinal grooves 20, extending from end to end thereof, the said grooves being 75 partly covered by metallic strips 20^a on opposite sides thereof, longitudinal slots being 80 formed between the said pairs of metallic strips. The said upper slats 21 are provided on their upper sides with keepers 22, which are here shown and preferably in the form of 85 rollers which are adapted to fit and slide in the grooves 20, the pivotal portions thereof forming the connections between them and said slats 21 being adapted to work in the open slots formed between the pairs of strips 90 20^a, forming the lower sides of the grooves 20. Prior to the formation of a mattress the said upper slats 21 are inserted or secured 95 under the follower and attached thereto by means of their keepers 22 in said grooves 20, 95 so that as the follower descends the stiffening-slats 21 are carried downward with it and compress the upper side of the bat. The bottoms of the press-boxes are provided on their upper sides with longitudinal grooves 24, in 100 which the lower slats 23 are inserted prior to the formation of the bat, and as the bat is ejected from the press-box into the tick by the means hereinafter described the said upper and lower stiffening-slats pass with the 105 said bat into the tick and are afterward withdrawn therefrom, the said stiffening-slats serving to stiffen the bat and secure the requisite rigidity while the bat is being inserted in the tick, as will be readily understood. 110

I will now describe an ejector mechanism by means of which the bats as the same are compressed and formed may be ejected from the press-boxes and forced into the ticks.

A transversely-disposed block J, made of 115 iron or other suitable material, is arranged on the bottom of each of the press-boxes and adapted to be moved longitudinally thereon and provided with a depending bracket O, which operates in a longitudinal slot P in the 120 bottom of the press-box and projects below the same a suitable distance. A screw-shaft Q passes through and engages a threaded opening in the lower portion of the said bracket O. Said shaft is provided against 125 endwise movement and has its ends journaled in bearings R S at opposite ends of the press-box and is provided with a miter gear-wheel 27, which is fast thereon. A shaft T is journaled in suitable bearings at the inner end 130 of the press-box, is provided with a miter gear-wheel U, which engages the miter-gear 27, and is provided at its outer end with a hand-crank V, whereby it may be manually

rotated. It will be understood that by turning the shaft T in one direction the block J may be moved outward on the bottom of the press-box, so as to eject the bat therefrom, 5 and by turning said shaft T in the opposite direction said block J may be run inward on the bottom of the press-box. The block J engages the inner ends of the stiffening-slats, and when the same is moved outward to eject 10 a bat from the press-box said block moves the said slats, together with the bat, into the tick, and the said slats are afterward withdrawn from between the tick and the bat before the end of the tick is sewed up.

15 The follower L corresponds in width with the narrowest mattress for the manufacture of which the machine is adapted, and when it is desired to make mattresses of greater width it is of course necessary to widen the said follower. To effect this, I provide extension-pieces 13, which are adapted to be placed on the sides of the follower and are connected together by transverse bars 12, which latter extend under the follower and fit in grooves 20 in the under side of the follower. In order to secure the extension-pieces to the sides of the follower, I provide brackets 17, which are preferably made of metal and are right angular in longitudinal section, as shown in Fig. 6.

25 The said brackets are secured on the upper sides of the extension-pieces 13 by means of screws, bolts, or in any other suitable manner, and are provided with hinged leaves 18, which are adapted to be folded on the upper side of 30 the follower, and are provided with longitudinal openings to receive the heads of turn-screws 15, which latter when the heads thereof are turned at right angles to the slots in the leaves, as indicated in dotted lines in Fig. 7, 35 serve to effectually secure the leaves to the upper sides of the follower, and thereby to secure the extensions to the follower, as will be readily understood. The follower may be of any suitable construction and may be made 40 of any suitable material. In the drawings I have shown the follower as being composed of boards connected together by brace-bars 14 on the upper sides thereof and forming a rigid frame. It will be understood that the 45 width of the extension-pieces 13 will be varied to suit the requirements of the case.

I will now describe means by which the follower may be operated.

A screw 1 has its lower end swiveled to the 55 center of the follower. The said screw passes through an opening 6, with which a supporting-standard 5 is provided, and on the said screw is a collar 8, which rotates in said opening 6, engages the threads of the screw, and 60 is provided at its lower end with a miter gear-wheel 7. Said gear 7 is engaged by a similar gear 4 on a shaft 3, which is provided with a crank 2, whereby it may be rotated. It is obvious that by this means the follower may be 65 raised and lowered by imparting rotatory motion to the screw 1. In order to prevent the follower from turning on the lower end of its

operating-screw 1, I provide vertically depending brackets 9, which have vertical guides 10, that engage notches 11 in the ends of the 70 follower as the latter is raised from the upper side of the press-box, and hence the follower is maintained in alignment with the press-box.

Having thus described my invention, I 75 claim—

1. In a mattress-press of the class described, in combination with a press-box having laterally-adjustable sides, whereby the width thereof may be varied, a follower, extension-pieces 80 adapted to be placed on the sides thereof and secured thereto, and cross-bars connecting said extension-pieces and disposed under the follower, substantially as described.

2. In a mattress-press of the class described, 85 in combination with a press-box having laterally-adjustable sides, whereby the width thereof may be varied, a follower, extension-pieces adapted to be placed on the sides thereof, and connected by cross-bars which bear under 90 said follower, hinged leaves on said extension-pieces, and fastening devices to receive said leaves on the upper side of the follower, substantially as described.

3. In a mattress-press of the class described, 95 the combination of a press-box having a discharge-opening, and a bottom provided on its upper side with longitudinal grooves, a follower or pressure-head having longitudinal grooves on its lower side, stiffening-slats in 100 said grooves of said follower and the bottom of the press-box, and an ejector adapted to force the bat, together with said stiffening-slats from between the follower and the bottom of the press-box, for the purpose set 105 forth, substantially as described.

4. In a mattress-making machine, a pair of connected press-boxes revolvable on a vertical axis and having discharge-openings, and a bat-ejector mechanism carried by each press-box at the lower part thereof, in combination with a feeding mechanism arranged in an overhead position to supply material to one press-box, a pressure mechanism in operative relation to the other press-box, and means for 110 operating the ejector mechanism, substantially as described.

5. In a mattress-making machine, a pair of connected press-boxes shiftable on a vertical axis and having discharge-openings, a bat-ejector device carried by each press-box at 120 the lower part thereof, and a common operating device connected operatively with each bat-ejector device and adapted to operate the latter subsequent to the compression of the 125 bat in said press-box, in combination with a distributing mechanism in operative relation to one press-box, and a bat-compression mechanism in a like relation to the other press-box, during the period of filling the first-named press-box by the feeding mechanism, substantially as described.

6. In a mattress-making machine, a pressure-head, and a series of slats detachably

connected to said pressure-head to travel therewith, in combination with a press-box within which the pressure-head and the slats thereof are adapted to traverse, means for operating the pressure-head, and a bat-ejector guided in the press-box to travel below the slats of the pressure-head, substantially as described.

7. In a mattress-making machine, a pressure-head consisting of a series of sections, and slats connected detachably to the lower side of the sectional head, in combination with a press-box, means for moving the pressure-head bodily with relation to the press-box, and a bat-ejector arranged to traverse the press-box below the slats on the pressure-head, substantially as described.

8. In a mattress-making machine, a sectional pressure-head consisting of a series of members arranged in the same transverse plane and each provided with a groove in its under side, a series of slats below the pressure-head, and means connecting the slats loosely with the grooved members of said head, in combination with a press-box, means for operating the pressure-head, and a bat-ejector arranged to traverse the press-box below the slats on the pressure-head, substantially as described.

9. In a mattress-making machine, the combination with a distributor and a vertically movable pressure-head, of a spindle occupying a fixed vertical position between said distributor and the pressure-head, a pair of connected press-boxes mounted idly on the spindle and shiftably thereon with relation to the distributor and the pressure-head, a bat-ejector device arranged to traverse the lower part of the press-box, and means for positively operating each bat-ejector, substantially as described.

10. In a mattress-making machine, the combination with a distributor, of vertical parallel guides disposed in the same horizontal plane as the distributor and at one side of the vertical plane thereof, a pressure-head shiftably confined in said guides, a pair of con-

nected press-boxes disposed below, and shiftable on a vertical axis with relation to, said distributor and pressure-head and each press-box provided with guides arranged to align vertically with the first-named guides, means for moving the pressure-head in a rectilinear path with relation to the press-box which is aligned vertically therewith, and a bat-ejector mechanism mounted to traverse the lower part of the press-box, substantially as described.

11. In a mattress-making machine, a shiftable press-box provided at one side thereof with a flap-door, a tick guide and spreader projecting from another side of the press-box in a plane at right angles to the flap-door, and a bat-ejector head carried by the press-box and arranged to traverse the chamber thereof in a path coincident with the plane of the tick guide and spreader, in combination with a pressure mechanism, and means for operating the bat-ejector head, substantially as described.

12. In a mattress-making machine, the combination with a feeder, and a pressure mechanism, of a pair of connected press-boxes shiftable on a vertical axis below said distributor and the pressure mechanism, a bat-ejector head slidably confined in the lower part of each press-box to be shiftable therewith and arranged to traverse the bat-compression chamber thereof, and means mounted on the press-boxes for individually operating said bat-ejector heads, substantially as described.

13. In a machine for making mattresses, the combination with a press-box having an opening on one side, through which the bat or felt may be ejected, a follower and means to operate the same, an ejector, and upper and lower slats movable with said ejector, for the purpose set forth, substantially as described.

Signed by me at San Antonio, Texas, this 1st day of September, 1898.

JOHN W. MORGAN.
